INVENTOR.

UNITED STATES PATENT OFFICE

169,082

SORORITY PIN

Thomas H. Neal, Kansas City, Mo.

Application October 30, 1952, Serial No. 22,065

Term of patent 14 years

(Cl. D29—2)

To all whom it may concern:

Be it known that I, Thomas H. Neal, a citizen of the United States, residing at Kansas City, State of Missouri, have invented a new, original, and ornamental Design for a Sorority Pin, of which the following is a specification, reference being had to the accompanying drawing, forming a part hereof:

Figure 1 is a front elevational view of a sorority pin embodying my new design;

Figure 2 and Figure 3 are side views taken from the left and right sides respectively of Figure 1;

Figure 4 is a top plan view thereof, and

Figure 5 is a bottom view thereof.

I claim:

The ornamental design for a sorority pin, as shown.

THOMAS H. NEAL.
